COVER FOR TOILET PAPER RECESS

Herman Rosenblum, 5905 Shore Parkway,
Brooklyn, N.Y.

Filed Aug. 3, 1960, Ser. No. 61,616

Term of patent 3½ years

(Cl. D4—3)

FIG. 1 is a front perspective view of a cover for toilet paper recess showing my new design, the rear not shown being plain;

FIG. 2 is a front elevation thereof;

FIG. 3 is an end view, the opposite side thereof being substantially the same and;

FIG. 4 is a top plan view thereof.

I claim:

The ornamental design for a cover for toilet paper recess, as shown and described.
